(57) **CLAIM**

The ornamental design for a reversible pet bed, as shown and described.

DESCRIPTION

FIG. 1 is a top plan view of a reversible pet bed showing my new design;

FIG. 2 is a bottom plan view thereof;

FIG. 3 is a right side elevation view thereof, the left side, front, and rear being a mirror image of the right side shown; and,

FIG. 4 is an isometric view thereof.
